UNITED STATES PATENT OFFICE.

FRANCIS K. HOLMESTED, OF CHARLESTON, AND THURSTON W. MITCHELL, OF HUNTINGTON, WEST VIRGINIA, ASSIGNEES TO STEEL PRODUCTS CO., OF HUNTINGTON, WEST VIRGINIA, A CORPORATION OF WEST VIRGINIA.

LOADING-MACHINE ATTACHMENT.

Application filed April 14, 1921. Serial No. 461,230.

To all whom it may concern:

Be it known that we, FRANCIS K. HOLMESTED and THURSTON W. MITCHELL, citizens of the United States, respectively residing at 5 Charleston, in the county of Kanawha, and Huntington, in the county of Cabell, and State of West Virginia, have invented new and useful Improvements in Loading-Machine Attachments, of which the following 10 is a specification.

This invention relates to improvements in machines for loading coal and other material, and consists essentially of improvements on the type of machine disclosed by 15 the patents of Francis K. Holmested, No. 1,290,200, of January 7, 1919, and 1,291,522, of January 14, 1919, and also illustrated and described in the application of John W. Houghton and Thurston W. Mitchell, Serial 20 No. 428,077. The improvement consists particularly in applying to the feed shovel or nose at the lower forward end of the inclined portion of a conveyer and cooperating with a reciprocating feed bar, forwardly 25 projecting material-dislodging means, which operate to cause the material to fall relatively to the bulk of material operated upon and drop on the feed shovel or nose. The primary object of the invention is to provide 30 means in connection with the feed shovel or nose at the forward extremity of a conveyer which will operate to facilitate loading of material with which the said shovel or nose is in engagement, especially 35 when the feed shovel or nose is withdrawn from and reset in operative position or penetration relatively to the material to be loaded.

In the accompanying drawing:

40 Fig. 1 is a side elevation of the feed shovel or nose at the lower end of a conveyer, showing the improvement applied thereto.

Fig. 2 is a top plan view of the feed shovel or nose as shown by Fig. 1 with the 45 improved attachment on opposite sides thereof, one side of the feed shovel or nose and one attachment being illustrated in horizontal section.

Fig. 3 is a detail perspective view of the 50 simplified form of the attachment.

Fig. 4 is a view similar to Fig. 3, showing a modification of the attachment.

As in the patented machines of Francis K. Holmested and the machine disclosed

by the pending application of Messrs. 55 Houghton and Mitchell hereinbefore referred to, a conveyer 5 is comprised in the cooperating components of the loading machine, said conveyer having opposite beams 6 which incline downwardly a suitable distance and connect with, or have applied thereto, a feed shovel or nose, generally indicated by the numeral 8. From the lower feeding shovel or nose 8 upwardly over the inclined portions of the beams 6 and continuing over the horizontal portion of said beams is a pan or trough 9, preferably formed of sheet metal of suitable thickness and firmly attached to the beams at opposite side edges. Suitable conveying means, 65 such as cross bars or lags 10, have close movement upwardly over the pan or trough 9 and are actuated by suitable mechanism forming no part of the present improvement. The feed shovel or nose 8 is of a 70 practically unitary structure, or, is composed of a metal strip or sheet of suitable dimensions bent over at opposite sides to provide U-shaped housings or angular guides 11 with their inner opposite sides 75 fully open. This shovel end or nose extends downwardly from the forward terminals of the beams 6 and for a greater portion of its length is straight and at the same inclination as the beams. The front extremity of 80 the feed shovel or shovel end or nose is horizontally flat, as at 12, and the terminating end thereof is beveled off, as at 13, in a downward and forward direction. Between the horizontal straight extremity 12 85 of the feed shovel or shovel end and the remaining straight inclined portion of the latter, a bend 14 is formed which is gradual and obviously necessary to dispose the said extremity 12 horizontally, and whereby the 90 forward extremity of the shovel end or nose may be caused to practically penetrate the coal or material to be loaded or operated upon by the machine. The curved bend of the shovel end or nose is regularly carried 95 out fully across the said end or nose and including the housings 11, and reciprocatingly mounted on and closely engaging the upper surface 15 of the shovel end or nose is a feed bar 16 which is angular in cross 100 section, the opposite ends of the said bar being freely movable in and covered by the housings or enclosing guides 11. The feed

bar 16 has a forward reduced edge 17 and a rear vertically straight side 18 disposed towards the movable elements of the conveyer. The rear straight side of the bar 16 5 provides a feeding shoulder to push coal or other material upwardly over the smooth surface of the shovel end or nose. To the opposite ends of the feed bar 16 flexible connections 19 are attached and composed of 10 a plurality of links pivotally jointed to permit the connections to freely move over the shovel end and conform to the configuration of the upper surface of the plate, which is regularly continued within the housings. 15 The connections 19 are given uniform and regular reciprocating strokes by actuating means, preferably consisting of slide blocks 20 mounted in the outer portions of the lower inclined extremities of the beams 6, 20 the said slide blocks having pitmen 21 pivotally attached thereto and operated by suitable driving mechanism to uniformly and simultaneously reciprocate the blocks 20 and actuate the flexible connections 19 25 and regularly move the feed bar 16 over the shovel end or nose, the said feed bar 16 being movable over the shovel end or nose such distance as to bring up the material being loaded into operative engagement 30 with the conveying means.

The foregoing structure is particularly disclosed by the application of Messrs. Thurston and Mitchell hereinbefore noted, and the improvement, as also hereinbefore indicated, consists of a material-displacing attachment, shown in detail by Fig. 3, and comprising a shank 22 conforming in longitudinal contour to the outer side of the shovel end or nose and having extending 40 horizontally therethrough a plurality of openings 23 to receive attaching bolts and nuts or analogous devices 24 which project outwardly from the opposite sides of the outer walls of the housings, for the flexible connections 19, as clearly shown by Fig. 2. The displacing attachment has at its forward end a fixed displacing wedge end or head 24 terminating in a rear vertically straight shoulder 25. One of these displacing attachments is applied to each side 45 of the shovel end or nose and may be adjusted longitudinally by disconnecting the same and subsequently resetting it as desired. The solid wedge ends or heads 24 project some distance in advance of the forward terminal of the shovel end or nose, so that when the said shovel end or nose is caused to penetrate the bulk of material to be loaded by the loading machine, the wedge 50 ends or heads 24 enter into the body or bulk of the material in advance of the said forward extremity of the shovel end or nose. When the shovel end or nose is withdrawn or moved rearwardly for the purpose of 55 resetting or repenetrating the same relatively

to the material to be loaded, the vertically straight shoulders 25 of the wedge ends or heads 24 drag the material forwardly therewith over to the feed bar 16, and, moreover, the bulk of material that may be standing above the wedge ends or heads 24 is caused to fall or drop over onto the forward extremity of the shovel end for engagement by the feed bar 16, with material advantages in facilitating the loading operation. 70 Instead of forming each displacing attachment with a single forward end or head 24 of solid wedge shape, each forward extremity of the attachment may be provided with a plurality of wedge devices 26, and the number of wedge devices may be increased as desired. When the wedge ends or heads 26 are used in plural form in connection with each displacing attachment, it will be understood that the latter will be modified in its proportions, which may be varied to accommodate the location of a number of wedge devices ahead of the forward extremity of the shovel end, the said plural wedge devices operating 85 similarly to the single wedge devices or heads 24 hereinbefore described. 90

The improved attachment is comparatively simple and may be applied to any machine now in use having corresponding devices, such as the reciprocating feed bar 16 or any other analogous feed means. 95

What is claimed as new is:

1. The combination with the shovel end of a conveyer of a loading machine having means for moving material to the conveyer, of a material-displacing attachment applied to the opposite sides and in part projecting materially in advance of the terminal of the shovel end in fixed horizontal positions each attachment having fixed wedge means on the upper edges thereof and adapted to penetrate the material and displace the latter when the shovel end is withdrawn from the material. 100 105 110

2. The combination with the shovel end of a conveyer held in horizontal engaging position with relation to the ground and having means for moving material upwardly thereover to the conveyer, of fixed material-displacing means applied to opposite sides of and in part rigidly projecting horizontally in advance of the front extremity of said shovel end and provided with rigid material displacing means. 115 120

3. The combination with the shovel end of a conveyer having means for moving material upwardly thereover to the conveyer, of fixed material-displacing means applied to opposite sides of and in part rigidly projecting horizontally in advance of the front extremity of said shovel end and provided with rigid material displacing means integrally formed therewith, each attachment being longitudinally adjustable with relation to 125 130

the shovel end to modify the projection thereof relatively to the shovel end.

4. The combination with a horizontally disposed shovel end at the front extremity 5 of a conveyer having means for moving material thereover into engaging position by the conveyer, of a rigid attachment secured to each side and projecting in advance of the front extremity of the shovel end, the 10 attachments having fixed penetrating wedge means with angular portions of the same transverse extent as the attachments to draw material towards the shovel end.

5. The combination with a conveyer having a shovel end at its forward extremity 15 provided with means movable thereover to dispose material in engaging position relatively to the conveyer, of displacing attach-

ments applied to the shovel end and having a straight projection in advance of the said end, said displacing attachments having one or more fixed wedge devices on the upper edges thereof for penetrating material and also drawing the said material towards the shovel end when the latter is withdrawn for 25 resetting purposes, said wedge devices being of the same transverse extent as the displacing attachments.

In testimony whereof we have hereunto set our hands in presence of two subscribing 30 witnesses.

FRANCIS K. HOLMESTED.

THURSTON W. MITCHELL.
